UNITED STATES PATENT OFFICE.

LLOYD D. JONES, OF CHRISTOPHER, ILLINOIS.

DISPENSING APPLICATOR.

Application filed March 17, 1924. Serial No. 699,852.

This invention relates to applicators for liquid material having means in conjunction therewith for dispensing predetermined quantities of liquid to the applicator portion 5 of the device to be applied in a suitable manner.

An object of the invention resides in providing an applicator in the form of a brush which is adapted to be provided with a container or tank for holding liquid material, and a dispensing and measuring chamber for receiving a charge of liquid from the tank to be dispensed through the applicator or brush, means being further provided for 15 controlling the admission of charges from the tank to the dispensing and measuring chamber.

Another object of the invention is to provide an applicator in the form of a brush 20 having the bristles mounted in a head and provided with outlet openings in the head mounting the bristles, a measuring and dispensing chamber being provided on the side of the head opposite to the bristles so that 25 liquid delivered thereto will be slowly discharged through the openings to the brush, while a tank is provided adjacent the dispensing chamber with a substantially large outlet opening communicating with the dispensing chamber and having manually controlled means operating a closure for the 30 opening, so that a charge of liquid may be admitted to the measuring and dispensing chamber in an exceedingly short space of 35 time and before or by the time it begins to flow through the outlet opening to the brush, so that the charge of liquid to be dispensed can be predetermined in substantially accurate quantities.

40 The invention also comprehends other objects and improvements in the details of construction and arrangement of the parts which are more particularly pointed out in the following description and claims, directed to a preferred form of the invention, it being understood, however, that variations in the form and arrangement of these parts may be made without departing from the scope of the appended claim.

50 In the drawing forming a part of this application:—

Figure 1 is a vertical sectional view through an applicator constructed in accordance with this invention.

55 Figure 2 is a detail view showing a sec-

tion of the bristle mounting and the manner of applying the outlet tube thereto.

1 indicates an applicator having a handle 2 and an enlarged head 3 which is hollowed out to receive the metallic tank member 4 60 which is adapted to contain suitable liquid which is put in the tank through a filling opening 5 closed by a cover indicated at 6, the bottom wall 7 of the tank 4 being provided with an enlarged central opening 8, 65 providing an outlet communicating with the dispensing and measuring chamber 9, which is formed in the flange extension 10 from the wall 7 of the tank 4 as is clearly shown in Figure 1 of the drawing. 70

The brush head 11 which fits in the outer edge of the flange 10 and cooperates with the wall 7 of the tank 4 to form the measuring and dispensing chamber 9 is provided with a plurality of openings 12 adapted to receive concentric tubes 13 around which are positioned the bristles 14 which are secured in the openings 12 in any desirable manner, such as by the binding ring 15, more clearly illustrated in Figure 2 of the drawings 80 which binds the bristles onto the tube 13 and which in concentric relation thereto, are adapted for a driving fit in the openings 12 of the brush heads 11. The inner or upper wall of the brush head 11 is provided with the socket 16 adapted to mount the bell crank lever 17, to one end of which is connected an operating rod 18 extending to the lever 19 carried in the recess 20 of the handle beyond the tank 4, as 90 may be clearly observed from Figure 1, so that the ends of the bell crank lever may be depressed by the finger for operating the bell crank lever 17, the other leg of which is connected by a link 21 to raise the closure member 22. The closure member includes a disc of substantially larger size than the opening 8 in the wall 7 of the tank which is provided with an annular seating member 23 having an internal annular recess for receiving the circumferential edge of the disc 22, said seat member being formed of rubber or other suitable material adapted to cooperate with the wall 7 beyond the opening 8 therein for closing the opening against the passage of liquid from the tank 4 into the measuring and dispensing chamber. A coil spring 24 arranged in frusto-conical or tapering form from one end to the other is inserted in 100 105 110

the tank 4 and normally under compression for forcing the disc 22 toward the wall 7 thereon and close the opening against the outlet of liquid from the receptacle, the link 5 21 being substantially short and guiding and centering the disc 22 relative to the opening 8 so that it will be always in a proper relation therewith.

From the above description, it will be seen 10 that when the tank 4 is charged with liquid, which for example may be hair tonic, or the like, the operating lever 19 may be depressed for locking the bell crank lever 17 on its pivot in the bracket 16 for raising the 15 disc 22 from the wall 7 of the tank and permitting the immediate discharge of a quantity of liquid from the tank into the measuring and dispensing chamber. By reason of the large size of the opening 8, the chamber 20 would be completely filled immediately after the opening of the valve or disc 22 and before the liquid has had sufficient time to discharge to any appreciable extent from the tubes 13 of the brush, so that a predetermined 25 amount of the liquid is measured in the measuring and dispensing chamber and the lever 19 released to permit the spring 24 to reseat the disc on the wall 7 and prevent a further discharge of the liquid from the tank 4. The brush may now be applied 30 to a person's head in case that it is desired to apply hair tonic and the tonic will be disposed from the measuring and dispensing chamber 9 in a gradual and slow manner 35 through the tubes 13 so that the applicator may be worked over the hair to which the tonic is to be applied for gradually applying it thereto and rubbing it into the hair, the amount of tonic contained in the dispensing 40 chamber 9 being sufficient to pro-

vide a single application to the hair for which a barber charges a certain sum.

More economical use and application of the hair tonic will thus result by using the present invention, and the customer will 45 always receive a full treatment.

It is to be understood, however, that while the above is given as an example of the use of this invention, it may be used in any case where an applicator is used for applying a liquid substance, and particularly where it is advantageous and substantially necessary to dispense predetermined quantities of the liquid to be applied. 50

What is claimed is:—

An applicator comprising a handle member provided at one end with an enlarged head, the head being provided, at one side, with a recess, a tank housed within the recess and having a flange disposed beyond the bottom wall of the tank, a brush head having perforations therethrough disposed within the flange and spaced from the bottom wall of the tank, said bottom wall of the tank being provided with a central 60 opening, a spring pressed valve located within the tank and normally closing the opening, a bell crank lever fulcrumed on the brush head adjacent the opening and having one of its arms operatively connected with the valve by a short link tending to maintain the valve centered in relation to the opening, a second bell crank lever fulcrumed upon the handle member, and a link 65 operatively connecting said bell crank levers together. 70

In testimony whereof I affix my signature.

LLOYD D. JONES. 75
